MULTI-FACET ACOUSTIC PANEL

John Christopher Jaffe, Norwalk, Conn., assignor to Stage-craft Corporation, Norwalk, Conn., a corporation of New York

Filed May 20, 1964, Ser. No. 30,072

Term of patent 14 years

(Cl. D13—1)

FIG. 1.

FIG. 2.

FIG. 3.

FIG. 4.

FIG. 5.

FIG. 9.

FIG. 7.

FIG. 1 is a front perspective view of a first embodiment of a multi-facet acoustic panel embodying my new design;

FIG. 2 is a side perspective view thereof;

FIG. 3 is a left side elevational view thereof;

FIG. 4 is a right side elevational view thereof;

FIG. 5 is a top plan view thereof;

FIG. 6 is an exploded rear elevational view thereof;

FIG. 7 is an exploded front elevational view thereof;

FIG. 8 is a side perspective view of a second embodiment thereof; and

FIG. 9 is a front elevational view of the top panel illustrated in FIG. 8.

The only differences between the two embodiments re-

side in the shape of the upper panel members as indicated by FIGS. 7 and 9.

I claim:

The ornamental design for multi-facet acoustic panel, as shown and described.
